UNITED STATES PATENT OFFICE.

WILLIAM E. S. McCORMICK, OF RUSH RUN, WEST VIRGINIA.

PORTABLE UNLOADING MACHINE.

Application filed April 4, 1924. Serial No. 704,187.

To all whom it may concern:

Be it known that I, WILLIAM E. S. McCORMICK, a citizen of the United States, residing at Rush Run, in the county of Fayette and State of West Virginia, have invented certain new and useful Improvements in Portable Unloading Machines; and I do hereby declare the following to be a full, clear, and exact description of the invention, such as will enable others skilled in the art to which it appertains to make and use the same.

The primary object of this invention is the provision of a machine for unloading slate or other refuse from mines and which is portable and automatic in operation, the loaded car or other carrier being automatically dumped and returned to a position so as not to obstruct the next car to be unloaded.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a side view of a portable unloading machine embodying the invention, the front portion of the tip or inclined runway being broken away,

Figure 2 is a side view of the front portion of the tip or runway and a portion of the truck,

Figure 3 is an enlarged view of the tipple and truck, parts being broken away,

Figure 4 is a view similar to Figure 3, showing the operation of the tipple by full and dotted lines,

Figure 5 is an enlarged rear view partly in section,

Figure 6 is a side view of the tipple,

Figure 7 is a horizontal sectional view on the line 7—7 of Figure 6,

Figure 8 is an enlarged detail sectional view on the line 8—8 of Figure 1,

Figure 9 is a detail sectional view on the line 9—9 of Figure 2, and

Figure 10 is a detail view of a portion of 55 the tipple supporting frame.

Corresponding and like parts are referred to in the following description and designated in the several views of the drawings by like reference characters.

A track 1 is preferably provided for the machine to run upon and this track may be extended as the unloading progresses and the track may be permanent or temporary, according to existing conditions. A suitable truck 2 is mounted upon the track 1 and may be of any construction. A supporting frame is mounted upon the truck 2 and comprises similar side structures, each including an upper longitudinal beam 3, a front upright 4, a rear inclined stay 5, and a front inclined brace 6 provided at its upper end with a guide pulley 7. The supporting frame is rigid and the component members may be of any construction and 60 jointed in any preferred way. A tip or inclined runway 8 is supported partly upon the truck 2 and partly upon the track 1 and is preferably of sectional formation, the front section being adapted to be secured to 65 the rails of the track 1 in any determinate way and, as shown, a shoe 9 is adapted to be fitted to the track rail and made fast thereto by clamp screws 10 which engage 70 under the head of the rail and bind against 75 the side web. (Fig. 9.)

A tipple 11 is pivotally mounted upon the supporting frame forming the superstructure of the truck 2 and is journaled between the rear ends of the side members, as indicated most clearly in Figure 5. The tipple 11 is provided at opposite sides with grooved segments 12 which are concentric with the journals 13 of the tipple and which have 80 rigid connection with the latter to pivot 85 therewith. A cable 14 or like connection is attached at one end to each of the segments 12 and passes over the guide pulley 7 and is provided at its lower forward end with a counterweight 15 which normally operates 90 to hold the tipple in a predetermined position. The tipple 11 is provided at its rear 95 end with a guide pulley 16 and beneath its rear portion with a similar guide pul-

ley 17. The tipple 11 includes side rails 18 which are adapted to register with the rails of the tip or inclined runway 8. The rear ends of the rails 18 curve upwardly and forwardly, as indicated at 18^a, whereby to engage the front wheels of a car 19, whereby to limit the movement thereof and retain the same upon the tipple during the dumping of the load. While the recurved ends 18^a 10 of the rails 18 are preferred as means for holding the car 19 upon the tipple, it is to be understood that other preferred means may be employed to subserve the same purpose.

15 A cross beam 18^b connects the forward ends of rails 18 and its horizontal flange is adapted to rest on the rails of runway 8 (Figures 6 and 7 in particular). One or more beams 18^c are fastened to the segments 20 12 and to the vertical flange of cross beam 18^b to brace and rigidify the latter.

25 A cable 20 or like part is adapted to be hitched at one end to the car 19 and its opposite end is connected to and adapted to be wound upon a hoisting engine which, in the present instance, is shown as comprising a drum 21 and a suitable operating motor 22, said hoisting engine being mounted upon the truck 2 or like part constituting 30 the portable base of the machine.

35 In the operation of the machine, it is transported to the required point of operation and is anchored to prevent movement thereof and, as stated herein, it is preferably mounted upon a track to which it is secured in the manner set forth and shown more particularly in Figure 9. The car or other carrier containing the load to be dumped is advanced to the tip or runway 40 and the cable 20 is attached thereto and upon starting the hoisting engine, the loaded car 19 is drawn over the runway and upon the tipple and when reaching the recurved portions 18^a of the track 18, a continued 45 operation of the hoisting engine causes the tipple to turn, as indicated by the full and dotted lines in Figure 4, thereby dumping the load. As the tipple 11 turns, the segments 12 correspondingly turn and effect 50 a lifting of the counterweight 15, and after the load has been discharged and the drum of the hoisting engine released, the tipple is returned to normal position and the empty car returned to the track 1 by gravitational 55 action on the tipple and runway. The empty cars may be side-tracked so as not

to interfere with the advance of the loaded cars to be unloaded in the manner stated herein.

What is claimed is:

1. In combination with a dumping tipple for unloading cars and the like, and having an inclined runway leading thereto, an angular cross beam secured to the end of the tipple and adapted to rest on the end 60 of said runway, a grooved segment secured to said tipple, a counterweight, a flexible member connecting said segment and counterweight, and a beam secured to said segment and engaging the angular cross beam 65 70 aforesaid.

2. In a portable unloading machine, a mobile body, a runway mounted on said body, a tipple arranged at the end of said runway, supporting means for said tipple 75 comprising a frame on each side of the runway comprising an upright, a stay, a horizontal beam connecting said upright and stay, and a brace secured to the mobile body intermediate of the upright and stay and to the joint between the upright and horizontal beam, the tipple being pivoted at the end of said stay, a grooved segment carried by the tipple, a counterweight, and a flexible element connecting said counterweight and grooved segment and trained over a pulley on the brace aforesaid.

3. A machine of the class described having a mobile body, an inclined runway extending partly across and supported by the body, a transverse shaft carried by the body, a tipple pivotally mounted by said shaft, said tipple being inclined and at its forward end resting on said runway, a car adapted to travel on said runway and tipple, means on the tipple engageable by the car to limit the movement of the latter onto the tipple and to hold the car during emptying, a hoist carried by said body, and an operative connection from said hoist to 90 said car engaging the tipple, whereby the car may be moved onto the tipple and the car and tipple thereafter unitarily tilted to empty the car, a segment carried by said shaft, a flexible element connected to said segment, a weight connected to said element, and means on the body guiding said element.

In testimony whereof I affix my signature.

WILLIAM E. S. McCORMICK.
